Primary Examiner — Shannon W Morgan*Assistant Examiner* — Terilyn Davis(74) *Attorney, Agent, or Firm* — FRESH IP PLC; Clifford D. Hyra; Micah C. Gunn(57) **CLAIM**

The ornamental design for a grill, as shown and described.

DESCRIPTION

FIG. 1 is a top, front, right perspective view of a grill;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is the grill of FIGS. 1-7 with the top cooking surface shown in an alternative configuration, all other aspects being identical.

The broken lines illustrate portions of the grill that form no part of the claimed design.

1 Claim, 8 Drawing Sheets(56)
